UNITED STATES PATENT OFFICE.

WALTER RAABE, OF COTHEN, ANHALT, GERMANY.

MULTICHAMBER APPARATUS FOR CONDUCTING LEACHING, WASHING, OR LIKE OPERATIONS ON SOLID OR SEMISOLID MATERIAL.

Application filed February 7, 1925. Serial No. 7,576.

To all whom it may concern:

Be it known that I, WALTER RAABE, residing at Cothen, Anhalt, in the German Republic, have invented certain new and useful

5 Improvements in Multichamber Apparatus for Conducting Leaching, Washing, or like Operations on Solid or Semisolid Material, of which the following is a specification.

This invention relates to apparatus for 10 treating liquid and solid or semi-solid material in admixture and has for its object an improvement in multi-chamber apparatus for conducting leaching, washing, or like operations on solid or semisolid material 15 particularly for leaching sacchariferous plant cuttings or slices on the countercurrent principle.

In older apparatus of this type it is already well known to improve the work by 20 providing between the leaching chambers partitions over which the material from which the sugar is to be removed is conveyed, separate from the liquid, by lifting members (see U. S. Patent No. 1,134,152).

25 It has been found that the separation of the solid substances from the liquid in such apparatus can be made still more complete if the material is passed over pervious surfaces, sieves, or the like arranged above the 30 liquid and the partitions, and the characteristic feature of the present invention is the provision of such surfaces.

The action is particularly favorable if the material is pressed with light pressure 35 against the pervious surfaces by the lifting members, as the separation of the material and the liquid is considerably enhanced thereby.

40 Sieves for the separation of the liquid from solid material are naturally known in general in leaching apparatus and it is also well known to form the lifting members pervious in the manner of sieves in such apparatus. These known arrangements, however, are insufficient for the purpose in view 45 and consequently the invention is directed to the provision and use of the additional pervious surfaces above referred to.

50 In the accompanying drawings is illustrated diagrammatically, by way of example, one constructional form of apparatus embodying the present invention.

In the drawings:

Fig. 1 is a partial longitudinal section of the apparatus, 55

Fig. 2 is a partial section corresponding with Fig. 1 but to a larger scale.

In the stationary trough or drum *a* the solid material, such for example the cuttings *b* (Fig. 2), is moved from right to left by 60 the delivery arms *d* secured to the shaft *c* and is intermixed with liquid flowing from left to right.

The trough or drum *a* is divided by partitions *d'* and *e* which between them enclose a separating chamber or damming chamber *f*. Within this is provided an overflow wall *g* over the top *h* of which the liquid, flowing from left to right under the action of the 70 inclination of the apparatus, flows in the direction of the arrow *i* (Fig. 2) from one leaching chamber to the next, while the cuttings *b* are conveyed oppositely thereto in the direction of the arrow *k* over the roof *l* of the separating chamber by lifting members or throwover devices *m*, which are also secured to the shaft *c*. All this is well known. 75

According to the present invention above the walls *d'* sieve-like or grid-like surfaces *n* pervious to liquid are provided along which the material *b* to be leached is conveyed by the lifting members *m*. The liquid still adhering to the material thus finds an opportunity of flowing through the surfaces *n* in order then to flow by way of the holes *o* in the roof *l* into the part of the separating chamber *f* to the right of the overflow wall *g* whence it flows back into the part of the leaching space which it has just left—with the consequence that a drawing-away of rich liquid into leaching chambers traversed by poorer liquid is prevented as much as possible. 90

As the throw-over devices *m* are set 95 against the walls *d'*, *n*, at an inclination in the manner of a screw surface, a light pressing of the material *b* against the sieve-like surface *n* takes place and thereby further improves the separation of the liquid.

The material then falls over on to the other side of the peak or top edge *p* of the wall *n* and over surfaces *r* which are preferably also constructed so as to be 100

previous to liquids. The front and rear pervious surfaces *n* and *r* constitute a roof-like structure over the separating chamber *f*. Through these surfaces *r* it is possible for any further liquid residues, which may have become separated, to flow back into the separating chamber *f* and again into the right hand part.

What I claim is:—

- 10 1. A multichamber leaching apparatus for solid and semi-solid material and more particularly for removing sugar from sacchariferous plant cuttings on the countercurrent principle comprising, a drum, partitions in the drum forming leaching chambers therein, lifting members for lifting the non-liquid material over the partitions, and liquid pervious surface members positioned adjacent the partitions so that the non-liquid material passes over the pervious surfaces in being lifted over the partitions.
- 15 2. A multichamber leaching apparatus for solid and semi-solid material and more particularly for removing sugar from sacchariferous plant cuttings on the countercurrent principle comprising, a drum, partitions in the drum forming leaching chambers therein, lifting members for lifting the non-liquid material over the partitions, and liquid pervious surface members positioned adjacent the partitions so that the non-liquid material passes over the pervious surfaces in being lifted over the partitions, the lifting members being positioned adjacent the liquid pervious surface members to exert a light pressure upon the cuttings which are against the pervious surfaces during lifting motion.
- 20 3. A multichamber leaching apparatus for solid and semi-solid material and more particularly for removing sugar from sacchariferous plant cuttings on the countercurrent principle comprising, a drum, partitions in the drum forming leaching chambers therein, lifting members for lifting the non-liquid material over the partitions, and liquid pervious surface members positioned adjacent the partitions so that the non-liquid material passes over the pervious surfaces in being lifted over the partitions, each partition forming a separating chamber, a transverse central overflow wall in each chamber, a perforated roof on each chamber, each pervious surface member being positioned adjacent a chamber roof.
- 25 4. A multichamber leaching apparatus for solid and semi-solid material and more particularly for removing sugar from sacchariferous plant cuttings on the countercurrent principle comprising, a drum, partitions in the drum forming leaching chambers therein, lifting members for lifting the non-liquid material over the partitions, and liquid pervious surface members positioned adjacent the partitions to that the non-liquid

material passes over the pervious surfaces in being lifted over the partitions, each partition forming a separating chamber, a transverse central overflow wall in each chamber, a perforated roof on each chamber, each pervious surface member being positioned above and enclosing a chamber roof.

5. A multichamber leaching apparatus for solid and semi-solid material and more particularly for removing sugar from sacchariferous plant cuttings on the countercurrent principle comprising, a drum, partitions in the drum forming leaching chambers therein, lifting members for lifting the non-liquid material over the partitions, and liquid pervious surface members positioned adjacent the partitions so that the non-liquid material passes over the pervious surfaces in being lifted over the partitions, each partition forming a separating chamber, a transverse central overflow wall in each chamber, a perforated roof on each chamber, each pervious surface member being positioned above and enclosing a chamber roof, the lifting members being positioned to the far sides of the separating chambers with reference to the direction of flow of liquid material.

6. A multichamber leaching apparatus for solid and semi-solid material and more particularly for removing sugar from sacchariferous plant cuttings on the countercurrent principle comprising, a drum, partitions in the drum forming leaching chambers therein, lifting members for lifting the non-liquid material over the partitions, and liquid pervious surface members positioned adjacent the partitions so that the non-liquid material passes over the pervious surfaces in being lifted over the partitions, the lifting members being positioned adjacent the liquid pervious surface members to exert a light pressure upon the cuttings which are against the pervious surfaces during lifting motion, each pervious surface member comprising a two-sided roof-like structure each side of which is pervious.

7. A multichamber leaching apparatus for solid and semi-solid material and more particularly for removing sugar from sacchariferous plant cuttings on the countercurrent principle comprising, a drum, partitions in the drum forming leaching chambers therein, lifting members for lifting the non-liquid material over the partitions, and liquid pervious surface members positioned adjacent the partitions so that the non-liquid material passes over the pervious surfaces in being lifted over the partitions, each partition forming a separating chamber, a transverse central overflow wall in each chamber, a perforated roof on each chamber, each pervious surface member being positioned adjacent a chamber roof, the perforation in the roof being positioned so that liquid passes through the pervious surfaces to that side.

of the overflow wall which is adjacent the separating chamber from which the liquid has just come.

8. A multichamber leaching apparatus for solid and semi-solid material and more particularly for removing sugar from sacchariferous plant cuttings on the counter-current principle comprising, a drum, partitions in the drum forming leaching chambers therein, lifting members for lifting the non-liquid material over the partitions, and liquid pervious surface members positioned adjacent the partitions so that the non-liquid material passes over the pervious surfaces in being lifted over the partitions, each parti-

tion forming a separating chamber, a transverse central overflow wall in each chamber, a perforated roof on each chamber, each pervious surface member being positioned adjacent a chamber roof, the perforation in the roof being positioned so that liquid passes through the pervious surfaces to that side of the overflow wall which is adjacent the separating chamber from which the liquid has just come, and means in each partition for 20 conducting the liquid passed through the pervious surfaces, back to the separating chamber from which it has just come.

In testimony whereof I affix my signature.
WALTER RAABE.
